THEODORE L. PATRICK, OF CARDWELL, MONTANA, ASSIGNOR OF ONE-HALF TO JOHN TRUZZOLINO, OF BUTTE, MONTANA

AIR PUMP

Application filed May 6, 1929. Serial No. 360,785.

This invention relates to air pumps and more especially to pumps of the double acting type, and my object is to produce a simple, strong, durable and efficient pump which will 5 enable motorists to quickly and easily effect inflation of tires or supply air under pressure for other purposes.

With this object in view the invention consists in certain novel and useful features of 10 construction and combinations of parts as hereinafter described and claimed; and in order that it may be fully understood, reference is to be had to the accompanying drawing, in which:

15 Figure 1 is a view partly in elevation and partly in central vertical section, of a double acting pump embodying the invention.

Figure 2 is a horizontal section on the line II—II of Figure 1.

20 Figure 3 is a horizontal section on the line III—III of Figure 1.

Figure 4 is a horizontal section on the line IV—IV of Figure 1.

Referring now to the drawing in detail, 1 25 indicates a suitable base provided in its upper side with a pair of circular recesses 2. It is also formed with a passage 3 connecting the two recesses and a passage 4 leading upward from passage 3, to a point exterior to 30 the said recesses.

A pair of cylinders 5 fit and are secured at their lower ends in the respective recesses with an air-tight relation. Secured to the upper ends of the cylinders is a cap or head, 35 composed of a pair of plates 6 and 7, spaced apart by a marginal gasket 8, and gaskets 9 are interposed between the head and the cylinders. The gasket 8 establishes an air-tight relationship between the plates of the head, 40 and by spacing said plates apart provides a passage or chamber 10 for the head. The gaskets 9 establish an air-tight relationship between the head and the cylinders, and the lower plate of the head is provided with passages 11 which respectively connect the chambers of the cylinders with the chamber 10 of the head.

50 Connecting the base and head between the cylinders, is a pipeway consisting of pipe sections 13 and 14 united by a union 15.

Pipe section 13 is equipped with a valve casting 16, containing a ball valve or plug 17 and a spring 18 for normally holding said ball valve pressed upwardly and seated so as to close communication between the valve casting and the air passage or chamber 10. A similar valve casting 19 is provided in the lower end of pipe section 14 and contains a ball valve or plug 20 and a spring 21, the latter acting to normally maintain the ball 60 valve 20 seated and closing communication between the valve casting and air passage 3. The pipe section 14 is also provided with a coupling 22 having a nozzle 23 for engagement by a flexible hose connection, not 65 shown, to supply air to a pneumatic tire or other object.

The upper plate of the head is provided in line with the axial center of each cylinder, with any suitable packing gland 23^a, and extending 70 slidingly through said packing glands and the head, are tubular piston rods or stems 24. Each piston rod or stem is equipped at its lower end with a pair of spaced pistons 25 and 26 of the cup-leather or equivalent 75 type, the pistons 25 facing downwardly and the pistons 26 facing upwardly, and between said pistons the respective stems are each provided with an orifice 27, it being understood that the stems below said orifices are 80 closed. The upper ends of the stems are open to the atmosphere as at 24^a and they are connected by a handle 28.

To operate the pump, the handle is grasped and when pressed downwardly imparts corresponding movement to the pistons. This effects expansion of pistons 25 which force the air from the lower ends of the cylinders into the passage 3 and upward within the pipeway, the pressure thus produced unseating 85 the ball valve 20 to permit the air to pass into the valve casing 19 and through the stem of the coupling 22, because at this time the ball valve 17 is seated, not only because the spring 18 normally holds said valve seated as explained, but because air passing up through the pipeway cooperates 90 with said spring in said action, and also because the downward movement of the pistons tends to create a vacuum in the upper ends 100

of the cylinders and the passage 10 to cooperate in the tight seating of said ball valve 17. As the downward movement of the pistons with valve 17 seated, tends to create a 5 vacuum above the pistons 25, there follows collapsing movement of the upper pistons 26 and results in air entering the upper ends of the piston stems or rods and passing through the orifices 27 into the space between the pistons 10 tons and then upward past the collapsed pistons to charge the cylinders above the bottom pistons with air at atmospheric pressure. When the downward movement of the pistons is followed by reverse or upward 15 movement thereof produced by pulling upward on the handle, the lower pistons collapse and the upper pistons immediately expand and thus draw air through the piston stems into the lower ends of the cylinder and 20 compress the air above them and cause it to pass through orifices 11 and the passage 10, and from the latter downward through pipe section 13 into the valve casing 16, this action unseating the ball valve 17 so that the air 25 can pass downward through the pipeway to the coupling 22, it being understood that as the upward movement of the pistons starts, the upward pressure on the ball valve 20 is removed to permit said ball valve to be instantly seated under the pressure of its spring 21 and the suctional pull created in the lower ends of the cylinders.

Upon the following downward and upward movements of the handle, the actions 35 just described are repeated. It will thus be seen that with each stroke of the pistons air is discharged from the coupling through its stem 23, and that in practice a constant stream of air is passing from the coupling. 40 The pump is therefore a double acting pump and will enable an operator to charge an inflatable tire or other object quickly and easily.

From the above description it will be apparent 45 that I have produced an air pump possessing the features of advantage set forth as desirable in the statement of the object of the invention, and which is susceptible of modification in various particulars within the principle of construction involved and the 50 spirit and scope of the appended claims.

I claim:

1. An air pump comprising a base, a pair 55 of cylinders secured on the base, a head closing the upper ends of the cylinders, a pipeway communicating at its opposite ends with the corresponding ends of the cylinders, a pair of normally-closed check valves for the pipeway, one adapted to open under air pressure 60 from the cylinders at one end thereof and the other adapted to open under pressure of air from the cylinders at the other end thereof, an air-discharge connection for the pipeway between the said valves, a pair of 65 simultaneously operable spaced pistons in

each cylinder for alternately forcing air toward the opposite ends of the cylinders, hollow piston rods carrying said spaced pistons, said rods having their bores communicating with the atmosphere at their upper ends and being closed at their lower ends, and cross bores connecting said piston rod bores above their closed lower ends with the spaces between the pistons. 70

2. An air pump comprising a base, a cylinder secured to and having its lower end closed by said base, a head secured to and closing the upper end of the cylinder, a pipeway communicating at its opposite ends with the opposite ends of said cylinder, a pair of 75 normally closed check valves for the pipeway, one adapted to open under air pressure from the cylinder at one end thereof, and the other adapted to open under pressure of air from the cylinder at the other end thereof, an air-discharge connection from the pipeway between said valves, a pair of simultaneously operable spaced pistons in the cylinder for alternately forcing air toward the opposite ends of the cylinder, a hollow piston rod carrying said pistons and being open to the atmosphere at its upper end and closed at its lower end, and a cross bore connecting said piston rod bore above its closed lower end with the space between said pair of pistons. 85

In testimony whereof I affix my signature.
